UNITED STATES PATENT OFFICE.

JAMES YOCOM, JR., OF PHILADELPHIA, PENNSYLVANIA.

LUBRICATOR.

SPECIFICATION forming part of Letters Patent No. 320,109, dated June 16, 1885.

Application filed May 14, 1885. (No model.)

To all whom it may concern:

Be it known that I, JAMES YOCOM, Jr., a citizen of the United States, residing at Philadelphia, Pennsylvania, have invented a new and useful Improvement in Lubricators, of which the following is a specification.

My invention relates to the self-oiling attachments of shaft-bearings.

The especial class to which it relates and the nature of the invention are more clearly indicated by a reference to the annexed drawings, in which—

Figure 1 is a vertical longitudinal section on a middle line of the lower half of a journal-box, and also of the depending oil-reservoir secured thereto, illustrating in the right-hand portion of the oil-reservoir the means heretofore employed for applying the wick, and in the left-hand portion my improved means. Fig. 2 is a top view of the oil-reservoir. Fig. 3 is a sectional elevation of the wick and inclosed spool and spring as heretofore used in connection with a socket, *d*, Fig. 1, for the spring to rest in. Fig. 4 is a sectional elevation of the wick and spring, showing a spool perforated to receive the upper end of a vertical rod, *m*, which is permanently fixed to the bottom of the oil-reservoir.

a represents the lower half of a journal-box; *b*, the oil-reservoir secured to the box *a* by screws *c*. *d* represents a shallow socket or

cup on the bottom of the oil-reservoir. *e* represents a tubular wick. *f* represents a spool, and *g* a spring, both inclosed in the wick. The lower end of the spring *g* rests in the 35 socket *d*, and the upper end of spring *g* abuts against the shoulder of spool *f*. The objection to thus combining the spool and spring with the wick is that the wick is free to shift its position and is thus made liable to miss 40 the aperture *h* opening into the bore of the journal-box when the oil-reservoir is being applied to the journal-box.

In my improved construction *i* represents the wick, *j* the spool, *k* the spring. *m* is a 45 vertical rod permanently affixed to the bottom of the oil-reservoir. The upper end of the rod *m* enters the aperture *n* in the spool, and acts positively to keep the wick in its proper position and cause it to enter the aperture *h* 50 opening into the bore of the journal-box when the oil-reservoir is being applied to the journal-box.

I claim—

In combination with the oil-reservoir of a 55 journal-box, the wick *i*, spool *j*, spring *k*, and fixed rod *m*, in the manner and for the purpose substantially as set forth.

JAMES YOCOM, JR.
